UNITED STATES PATENT OFFICE.

JOHN H. MORROW, OF CHICAGO, ILLINOIS.

FURNACE.

1,118,143.

Specification of Letters Patent. Patented Nov. 24, 1914.

Application filed May 31, 1912. Serial No. 700,719.

To all whom it may concern:

Be it known that I, JOHN H. MORROW, a citizen of the United States, residing at Chicago, in the county of Cook and State of Illinois, have invented certain new and useful Improvements in Furnaces, of which the following is a specification.

My invention relates in general to furnaces, and more particularly to means for consuming the smoke incident to burning soft coal.

Various mechanisms have heretofore been devised for consuming the smoke generated when a furnace is fired with soft coal. Many of such mechanisms have comprised means for feeding steam to the furnace fire-boxes, while others have consisted of means for regulating the dampers. Most of such mechanisms have been so complicated as to be impractical, and substantially all of them have proved inefficient.

During the practical operation of furnaces in which it was necessary for economical reasons to burn soft coal in localities where the smoke of chimneys is prohibited, I have discovered that by gradually closing the furnace fire-doors, after throwing each fresh charge of coal on the fire, so as to permit a gradually diminishing volume of air to be supplied through the fire-doors, the volatile matter of the coal, which would otherwise be carried up the stack as black smoke, will be so completely consumed as to prevent the smoking of the stack. I have further discovered that in order to obtain the best results, it is necessary to regulate the speed at which the fire-door is closed after the supply therethrough of each charge of fresh fuel, according to the character of the fuel, the draft, and the condition under which the furnace is operated, thereby so regulating the volume of air supplied through the fire-door as to produce a complete consumption of the smoke.

The object of my invention is, therefore, to provide the fire-doors of furnaces with means for automatically gradually closing the same after the supply of each charge of fresh fuel therethrough, so as to permit a gradually decreasing volume of air to be supplied to the fire sufficient to consume the smoke.

A further object of my invention is to provide the fire-box of a furnace with adjustable means for gradually closing the same after the supply of each fresh charge of fuel, so that the volume of air supplied

to the fire may be varied according to the character of the fuel, the degree of the draft, and the condition under which the furnace is operated, thereby rendering it possible to secure the conditions necessary to consume the volatile matter of the fuel which would otherwise form smoke.

A still further object of my invention is to provide a furnace with means for securing the consumption of the smoke, which will be simple in construction, convenient in application, and efficient in use.

My invention will be more fully disclosed hereinafter with reference to the accompanying drawing, in which the same is illustrated as embodied in a convenient and practical form, and in which—

Figure 1 is an elevational view of a portion of a furnace; Fig. 2, an enlarged sectional view on line 2—2, Fig. 1; and Fig. 3, an enlarged sectional view through the door closing means.

The same reference characters are used to designate the same parts in the several figures of the drawing.

Reference letter A designates a portion of the front wall of a furnace of any ordinary character and construction.

Reference characters B' and B² designate the usual fire-doors through which the charges of fuel are supplied to the fire.

Reference characters C' and C² designate the usual ash doors.

Reference characters D' and D² designate automatic devices for controlling the closing of the fire-doors B' and B², respectively. The controlling devices D' and D² do not *per se* constitute my invention, but may consist of door checks of such construction as to secure the automatic closing of the fire-doors in the manner necessary to embody my invention.

In the embodiment of my invention shown in the drawing, the door checks are mounted upon the door and are operatively connected by links E' and E², respectively, with the adjacent wall of the furnace.

F' and F² designate the operating arms of the devices D' and D², which arms are connected at their outer ends to the outer ends of the respective links E' and E², and at their inner ends to retarding mechanism. Each of the arms F' and F² is provided with a spring detent G, which, when the corresponding furnace door is open, will engage within a notch H formed in the upper surface of the underlying casing of the devices D' and D², so as to retain the door in open

position. Each of the door closing devices D' and D² may be conveniently constructed as shown in Fig. 3, in which the vertical shaft D, to which the inner end of the corresponding arm F' or F² is rigidly connected, is provided at its lower end with a crank d pivotally connected by a link d' with a piston d² which is adapted to reciprocate within a cylinder D³.

10 d³ indicates a check valve which opens to freely permit the passage of the retarding fluid therethrough when the furnace door is opened, but which will prevent the fluid passing through the piston when it moves in a direction to close the furnace door.

15 d⁴ indicates a by-pass extending around the piston and which is controlled by a needle valve d⁵. It will be obvious that by adjusting the needle valve, the flow of the 20 fluid through the by-pass d⁴ may be regulated and the speed at which the door will be closed will be thereby varied.

The operation and manner of using my improvement are as follows: The furnace doors are opened preparatory to supplying 25 fresh charges of coal through them to the fire. The opening of each door moves the upper end of the casing of the door closing device relatively to the spring detent G until the latter engages within the notch H, thereby holding the door open. After the fuel has been supplied, the door is given a slight push inwardly, thereby unseating the 30 detent G from the recess H and permitting the spring D' to become effective in closing the door. The operation of the spring is controlled by the movement of the piston d² within its cylinder, which in turn is dependent upon the by-passing of the fluid 35 through passage d⁴. The needle valve d⁵ is adjusted so as to vary the closing of the door according to the character of fuel which is used, according to the efficiency of the draft, and according to the requirements of each 40 particular furnace. It is necessary that there should be a sufficient volume of air supplied through the fire-door to insure the consumption of the volatile matter to the fuel which would ordinarily pass up the 45 stack as black smoke. By adjusting the needle valve d⁵ and observing the stack after the supply of fuel, it may be readily determined whether a sufficient quantity of air is being supplied after each charge of fresh 50 fuel to consume the smoke, and, if not, the needle valve d⁵ may be further adjusted until the desired result is secured.

55 From the foregoing description it will be observed that I have invented a simple and economical means for consuming smoke, which will not only avoid the disagreeable effects due to the smoke ordinarily generated in burning soft coal, but will contribute to

the economical running of the furnace by insuring the consumption of the particles of 65 the fuel which would otherwise be carried up the stack in the form of smoke. It will be further observed that my invention is applicable to furnaces already in use and may be adjusted according to the conditions of 70 each particular furnace, and according to the character of the fuel burned, so as to accomplish equally efficient results regardless of the special conditions existing at each furnace to which it is applied. 75

I claim:

1. The combination with a furnace, of a fire-door through which fuel is supplied, and means for automatically permitting a gradually reduced volume of air to be admitted through said fire-door after the supply of fuel therethrough, said means comprising a door check operatively connected directly with said door for gradually closing the same. 85

2. The combination with a furnace, of a fire-door through which fuel is supplied, and means for automatically permitting a predetermined gradually reduced volume of air to be supplied through said door after 90 the supply of fuel to the fire, said means comprising a door check operatively connected directly with said door and having adjustable means to regulate the closing of the door according to the character of the 95 fuel, draft, and requirements of the furnace.

3. The combination with a furnace, of a fire-door through which fuel is supplied, and means operatively connected directly to said door for holding the same open during the supply of fuel therethrough, and for automatically closing said door at a predetermined speed to permit a gradually decreasing volume of air to be supplied to the 100 fuel. 105

4. The combination with a furnace, of a door through which fuel is supplied, a door check connected directly to said fire door and to the front wall of the furnace adjacent thereto for automatically gradually closing said door and thereby permitting a gradually reduced volume of air to be admitted directly through said door after the supply of fuel therethrough, and means for adjusting the operation of said door check 110 to vary the rapidity with which the fire door is closed according to the character of the fuel and draft and the requirements of the furnace. 115

In testimony whereof, I have subscribed 120 my name.

JOHN H. MORROW
